SUPPORT AND PACKAGE FOR DISPENSING
TIE-STRINGS

Charles J. Lippold, Washington, D. C.

Application August 26, 1931. Serial No. 559,553

6 Claims. (Cl. 206—64)

This invention relates to supports, also to packages, and especially to a combined support and package for dispensing tie-strings.

Inventor has observed that much time is wasted by employees of the U. S. Post Office Department in tying packages by the old and crude way of tying the strings in knots, and that much string is wasted because it is difficult and tedious to untie the knots; hence the strings are cut, thrown into a pile, become tangled, and are therefore useless for tying other packages. Applicant invented and patented a string fastener to overcome the difficulties above mentioned, but has succeeded only in part, for the string fastener of his Patent No. 1,635,283 does not overcome the difficulty of the strings becoming tangled.

One object of the present invention, therefore, is to overcome the difficulty of the tie-strings becoming tangled, so they can be quickly and easily dispensed, one at a time, in an immediate usable condition, and can be used over and over many times. While this is practical and important in the use of tie-strings other than those shown in my Patent No. 1,635,283, it is particularly so in connection with my string fastener which is relatively expensive as to first cost, but very economical in saving time while rendering the tying of packages very secure.

A further object is to provide an improved tie-string holder or dispensing support which combines with a mass or bunch of strings for holding one another individually clamped or frictionally clasped so the individual strings can be quickly and easily withdrawn or dispensed while the remainder of the bunch remain practically undisturbed until they are respectively and individually pulled from the bunch.

A further object is to provide a quick, easy and practical means and method of packaging the strings and their support for handling and shipping without any danger of them becoming tangled or snarled when a number of such packages are massed for storage and shipment in a mail-bag or other receptacle.

Other objects and important features are pointed out or implied in the following details of description, in connection with the accompanying drawings in which:

Fig. 1 is a front view of one of my tie-string supports holding a small package or bunch of tie-strings which include the string-fastener shown in the patent referred to, a single one of such tie-strings, at the upper part, being in the position as if being manipulated into the receiving gap at the upper ends of the string-receiving

slots, a suspending means being shown at the upper end.

Fig. 2 is an enlarged view, or approximately the size used in actual practice for heavy tie-strings such as used to tie bundles of letters in the Post Offices of the U. S., of the clamping and supporting unit made according to a form of the invention that is found to be very practical and effective.

Fig. 3 is an edge view or right-side view of the device shown in Fig. 2.

Fig. 4 is a view similar to Fig. 1, but showing the tie-strings looped and tied with an individual one of the tie-strings and thereby made fast to the hooked intermediate part of the unit which is shown separately in Figs. 2 and 3.

Fig. 5 is a view similar to Fig. 1, but showing ordinary tie-strings without my string-fastener, and also showing a sheet of paper around one pendant part of the string-group and between the latter and the other pendant part of the string-group, this representing the first step in the method of forming the modified form of package shown in Fig. 6.

Fig. 6 shows a complete form of package that may be made from the paper, strings and string-support shown in Fig. 5.

Fig. 7 is an elevation of a modified form of the invention, as seen from the rear side, or opposite side from that of Fig. 2.

It should be understood that, in practice, the tie-strings are longer than illustrated in these drawings, but that the principles and methods remain the same, regardless of the length or variations in lengths of the strings, and that either method (here illustrated) can be used with either the plain or the improved tie strings here shown, or with other kinds of tie strings or string fasteners.

Referring to these drawings in detail, in which similar reference numerals correspond to similar parts in the several views, the invention is now described in detail as follows:

The supporting and clamping or clasping unit, shown in all the views, and shown separately in Figs. 2 and 3, is here shown as formed of a single length of wire, but as it may be formed with numerous differences, its detail description will have special reference to its functional nature and its general mechanical characteristics. This unit comprises an elongated body having a lateral extension 10 at its intermediate part, a loop or suspending means 11 at its upper end, a closed lower end 12, two substantially straight and parallel elements 13 extending between and united

with the lateral extension or hook 10 and the closed lower end 12, and an intermediate or central upright 14 extending between and united with the parts 11 and 12 while spaced from the 5 elements 13 and in parallel relation thereto so as to form two parallel slots 15 which have closed lower ends and open upper ends.

My patented tie strings are indicated at 16; the ordinary tie strings, at 16a; and the packaging paper, at 18. A hook 19, or other appropriate supporting or suspending means may be employed for removably connecting the suspending means 11 to a ceiling or wall of a room in which the packages are tied and untied, so it will be in a 15 convenient position for passing the strings, individually or in small bunches, into the receiving gap or opening 17 at the upper ends of the slots 15 and between the part 14 and loop or hook 10. When the strings are clasped between the elements 13 and 14, as in Figs. 1 and 5, any one of them can be pulled longitudinally and thus dispensed from the bunch without disturbing the latter. If any one of the strings is held by a 20 knot therein, it may be left until the last, when the other strings have been dispensed, whereupon it can be either pulled or lifted out of the slots.

In forming the package for preventing displacement or tangling of the strings in transportation, the lower free ends (in Figs. 1 or 5) are 30 bound together so they can not tangle, and one of the tie-strings may be used in binding them, as shown in Figs. 4 and 6, at 16b and 16c respectively. The same tie-string that binds the bunch also extends around the supporting unit, in direct engagement with the hook 10, or near thereto and between the hook and the closed lower ends of the slots 15, so the open ends of the slots are practically closed by the binding tie-string 16b or 16c, and the bunch can not move out of the 40 slots. Therefore, when the binding tie-strings are loosened, the package is immediately converted from a shipping package to a dispensing package. In practice, the strings being longer than shown in the drawings, the binding string should 45 be passed through the suspending eye 11, as well as engaged with the hook 10, in absence of the paper 18 as well as when such paper is used; and where the strings extend a considerable distance beyond the lower edge of the packaging paper, 50 such string-ends may be folded back within the folds of the paper after the latter has been wrapped around the upper parts, thus separating them from the lower parts so as to prevent entanglement therewith.

55 In the form of supporting unit here shown, the hook 10 not only serves to cooperate with the binding tie-string as described or explained in the foregoing, but it also constitutes the uniting and rigidifying element that holds the other parts 60 intact and in cooperative relation to one another, for although the parts may be soldered or welded together at 20, for sake of cooperation in making the device more rigid and stable, such soldering or welding could be omitted without impairing 65 the utility of the device to any considerable extent.

In Fig. 7, is shown a form of the tie-string supporting unit wherein the soldering is omitted, and a slidable sleeve 21 of leather, rubber or other 70 appropriate material is used; when made of leather, a rivet 22 extends through the edge-portions which project laterally so as to form a handle by which the sleeve can be slid down on the part 14, past the part 10 and onto the top of the 75 bunch of strings held therein as in the forms

shown in Figures 1 to 6 inclusive. Another distinction between the form shown in Fig. 7 and the other form, is that this form has a space 23 between the elements of the part 14, and that the material is springy to cause the part 14 to expand laterally and thereby hold the sleeve by its outward pressure and consequent friction, but permits the sleeve to be manually moved down while it presses the elements of part 14 inward or towards one another. By this means, a dual function is accomplished, (1) holding the eyes 11 in registration while the suspending hook is passed therethrough, and (2) holding the strings compact when it is slid down and frictionally held against them by the outward spring pressure of the part 14 against its inner surface. By thus holding the strings compact, I avoid the annoyance of pulling several strings when only one at a time is desired.

80 Of course, it is understood that when the strings are long and are folded back and forth between the folds of paper, and especially when the slots 15 are full or nearly full, the package will be 85 much larger than shown, in proportion to the size of the supporting units, the present drawings 90 showing the bunches containing only a few strings, to avoid unnecessary work and confusion.

95 Although I have described this invention very specifically, according to the embodiments shown, I have no intention to limit my patent protection to these exact details of description, for the invention is susceptible of numerous changes within the scope of the inventive ideas, as implied and claimed.

100 What I claim as my invention is:

1. In a unit for supporting and dispensing a bunch of tie-strings, an elongated body having a suspending element at its upper end, a closed lower end, an intermediate part projecting laterally beyond the parts at the upper and lower ends, and parallel slots extending up from said closed lower end to said lateral projection and having open upper ends for receiving tie-strings to be passed down and removably held at said closed lower end, said lateral projection being cooperative with any one of the tie-strings for closing the upper ends of the slots and thereby preventing accidental displacement of the bunch of tie-strings through said upper ends of the slots.

110 2. In a unit for supporting and dispensing a bunch of tie-strings, a body having normally upright slots which are closed at their lower ends and open at their upper ends for receiving tie-strings to be passed down the slots and be held in said lower ends of the slots so as to be pulled 115 longitudinally one at a time from the slots, and means movably engaged with said body for downward movement and pressure on said tie-strings for holding them compact, for the purpose specified.

120 3. The structure defined by claim 2, said body being springy and laterally expandable and contractible, the said means comprising a sleeve surrounding a part of said body and frictionally held in different adjusted positions by lateral expansion and spring pressure.

125 4. In a unit for supporting and dispensing a bunch of tie-strings, a body having normally upright slots which are closed at their lower ends and open at their upper ends for receiving a 130 bunch of tie-strings to be passed through said upper ends and down to the closed lower ends and held therein for being pulled longitudinally and thus dispensed one by one, and an arched or outwardly curved lateral projection crossing 135

over the upper ends of the slots for the purposes specified.

5. In a shipping package which is convertible into a dispensing package for dispensing tie-strings, the combination of an elongated member having parallel slots which are closed at one end and normally open at the other when in use as a dispensing package, said member having a lateral projection at the normally open ends, tie-strings extending through said slots and forming a bunch on said closed ends thereof, and binding means surrounding said bunch of tie-strings and engaged with said lateral projection

in such manner as to substantially close the normally open ends of the slots and prevent the bunch from passing out through said slots while preventing the tie-strings from becoming entangled with one another.

6. The structure and combination defined by claim 5, said elongated member having a suspending element at its upper end, said binding means being engaged with said suspending element and surrounding said bunch thereat for cooperation with said lateral projection in securing the package against opening and tangling.

CHARLES J. LIPPOLD.
